UNITED STATES PATENT OFFICE.

CLARENCE A. VETTER, OF PITTSBURGH, PENNSYLVANIA

INCANDESCENT ELECTRIC LAMP.

1,157,464.

Specification of Letters Patent. Patented Oct. 19, 1915.

Application filed July 31, 1913, Serial No. 782,374. Renewed January 7, 1915. Serial No. 1,047.

To all whom it may concern:

Be it known that I, CLARENCE A. VETTER, a citizen of the United States, residing at Pittsburgh, in the county of Allegheny and 5 State of Pennsylvania, have invented certain new and useful Improvements in Incandescent Electric Lamps, of which the following is a specification.

This invention relates to that class of 10 sockets or holders for incandescent electric lamps which are provided with locking means to prevent the unauthorized removal of the lamp.

In an application Serial No. 722,150, I 15 have described and claimed means to prevent the unlawful removal of tungsten and other high priced lamps from their sockets or holders, which means embodied an interlocking connection such that the lamp bulb cannot 20 be removed without breaking.

The present invention is an improvement thereon, and has for its object to provide a socket with locking means, which without impairing the efficiency of the lock is so arranged 25 that the lamp may be removed by an authorized person without breaking it.

The invention comprises the construction and arrangement of parts hereinafter described and claimed.

30 In the accompanying drawing, Figure 1 is an elevation of a portion of an incandescent lamp socket, partly broken away to show the improvements; Fig. 2 is an elevation of the same taken at right angles to the 35 view shown in Fig. 1; and Figs. 3 and 4 are respectively plan and edge views of the key.

In the drawing, the numeral 1 indicates the shell of an incandescent lamp socket, which may be of the usual or any desired 40 form, and is shown as enlarged at its upper portion where the usual insulating body 2 is located, and is contracted at its lower portion wherein is contained the usual threaded sleeve for receiving the shank of the lamp or 45 bulb. The body 2 will preferably be formed of porcelain, as is the usual practice. Located immediately adjacent and below the insulating body 2 is a disk 3, also of insulating material, such as porcelain, and to which 50 will be attached the threaded sleeve for receiving the lamp socket, said disk 3 being rotatably connected to the body 2, as is usual in this type of lock socket.

The disk 3 is formed on its periphery with 55 a key engaging part which is shown as an abutment or shoulder formed by a wall 4

of a recess in the periphery of the disk, and the shell has an opening 5 in the same general plane as the disk 3, and on its outside there is attached, as by rivets 7, a fitting 6 which is provided with a key way 8 extending therethrough and registering with the opening 5. The key way admits of the insertion of a suitable key or locking member 9 (Figs. 3 and 4) which when inserted engages the key engaging part 4 in the disk 3 and holds the latter from turning with the lamp. To prevent tampering with the lamp a threaded bore or passage 10 is formed in the fitting 6 and crosses the key way at a right angle thereto. In this threaded bore is a set screw 11 which, when screwed inwardly closes the key way and prevents the insertion of the key. This set screw is provided with a special head, preferably triangular, as shown at 12, and the key 9 is provided with a correspondingly shaped socket 13, by means of which the screw 11 can be rotated to clear the key way. The key is provided with wings 14 for its easy manipulation.

In the use of the invention the screw 11 is backed out to clear the key way, after which the shank of the key is inserted through the key way and into contact with the key engaging part 4, thus holding against rotation the disk 3 and the lamp receiving sleeve connected therewith. This enables the lamp to be either screwed in or screwed out of the socket. The key is then removed and the screw 11 screwed inwardly to close the key way. An unauthorized person is unable to then remove the lamp because the lamp receiving sleeve and the disk 3 will rotate freely and prevent disengagement of the lamp from the sleeve.

The disk 3 of insulating material is located immediately adjacent and below the insulating body 2 and is of very nearly the same diameter as the latter, and of greater diameter than the contracted lower portion of the shell and, therefore, of greater diameter than the lamp receiving threaded sleeve, so that said disk 3 projects peripherally beyond the metal portion containing the lamp. Consequently, it is impossible for the key when inserted to come in contact with any live metal portion, whereby injury or danger to the operator is avoided.

What I claim is:—

1. In an incandescent lamp socket, the combination of a shell, a member rotatable

- therein, a fitting secured to said shell and provided with a key way and with a threaded bore crossing said key way, a key adapted to enter said key way and engage said rotatable member and hold the same against rotation and having a wrench head, and a set screw adapted to said threaded bore and having a head which is a complement of the wrench head.
- 16 2. In an incandescent lamp socket, the combination of a shell, a member rotatable therein, a fitting secured to said shell and provided with a key way and with a passage crossing said key way, a key adapted to enter said key way and hold said rotatable member against rotation, and a barrier adapted to said crossing passage and having an operating portion adapted to be engaged by the key.
- 17 3. In an incandescent lamp socket, the combination of a shell, an insulating body whereof a part is stationary in the shell and a part rotatable with the lamp, means for holding said latter part against rotation, and a barrier arranged to prevent said holding means from engaging said rotatable part.
- 18 4. In an incandescent lamp socket, the
- combination of a shell provided with a key way, of a body of insulating material in said shell and stationary therein, of an insulating disk rotatable relative to said insulating body and with the lamp and located immediately adjacent said insulating body and provided on its periphery with a key engaging part which is removed from the lamp receiving threaded metal sleeve, and a key adapted to be inserted through said key way to engage only said insulating disk.
- 19 5. In an incandescent lamp socket, the combination of a shell provided with a key way, of an insulating body stationary in said shell, an insulating disk located directly adjacent said insulating body and rotatable thereon and with the lamp and projecting peripherally beyond the lamp receiving threaded metal sleeve and provided with a key engaging part, and a key adapted to be inserted through the key way in the shell and engage only said insulating disk.
- 20 In testimony whereof I affix my signature in presence of two witnesses.
- CLARENCE A. VETTER.
